PRINTING MACHINE

Carl J. Hueber, East Cleveland, Ohio, assignor to
Addressograph-Multigraph Corporation, Wil-
mington, Del., a corporation of Delaware

Application August 3, 1940, Serial No. 350,678

21 Claims. (Cl. 101—56)

This invention relates to printing machines and more particularly to structural sections adapted for use therein.

In printing machines of the character through which printing or like devices are sequentially fed, it is customary to feed the devices through the machine in a step-by-step manner and in the course of such movement the devices come to rest in printing position in the machine whereat impressions are made therefrom. While a wide variety of printing devices, of the character sequentially fed through printing machines such as those to which the present invention pertains, have heretofore been provided, that disclosed in Mohler Patent No. 1,812,894, patented July 7, 1931, is typical of such devices. A printing device of this kind includes a carrier or frame having an embossable metal plate removably retained in position thereon, type characters being embossed on such a plate to appear in relief on the operative face thereof. Type characters have also been embossed in a so-called one-piece printing device of the character disclosed for example in Duncan Patent No. 1,026,246, patented May 14, 1912, and devices of this character are frequently utilized in printing machines of the kind to which this invention relates. Furthermore, in some instances type characters have been formed in suitable stencil paper, carried by a frame of cardboard or other material, and suitable means have been provided in printing machines through which such devices were fed to apply ink to the type characters on printing devices of this character and for pressing a sheet into engagement with the inked type characters to thereby have an impression made thereon. Irrespective of whether printing devices embodying embossed type characters, or type characters afforded in a stencil sheet, were utilized, it has been necessary, in printing machines through which the devices were passed, to apply appreciable pressure in order that clear cut and otherwise satisfactory impressions would be produced in the machine.

In the printing machines through which printing or like devices of the aforesaid character, for example, are sequentially fed, the printing devices, in the course of the step-by-step movement thereof through the machine, come to rest at printing position in the machine on an anvil beneath an ink ribbon and a platen or other suitable means is operated to force a sheet overlying the ink ribbon toward type characters on the device whereupon an impression is made on the sheet from the type characters. Heretofore flat

and roller platens have been employed in printing machines of the aforesaid character. A flat platen of this character has customarily included a head embodying a flat face of resilient material, the head having been carried by an arm which was reciprocated to move the flat resilient face on the head to and from the operative position whereat impressions were made from the printing device at printing position in the machine in the aforesaid manner. A typical roller platen such as has been heretofore employed has included a resilient periphery and has been so mounted in the machine that it was movable to and from operative cooperation with a printing device on the anvil and customarily such a platen has been rolled across the type characters on the printing device on the anvil to effect a printing operation.

Heretofore it has been customary to mount the anvil, or other means on which the printing devices come to rest during the time impressions are made therefrom, on the frame of the machine and to also mount the platen, or other means operative to press the sheets into engagement with the type characters on the printing device resting on such an anvil, on the frame of the machine. In such an arrangement the stresses attendant to the application of pressure to effect the printing operation have been transmitted through the frame of the machine. This has necessitated that such frames be of rigid construction so as to be capable of dissipating the stresses attendant to the printing operations without undue deflection occurring in the various operative parts. This has also required that the operative parts themselves be constructed so as to effectively resist material deflection. It will be appreciated that deflection in the frame of printing machines or in the parts operative to effect printing operations in such machines might result in smudging the impressions, or in the production of uneven impressions, which is to say, the making of some parts of an impression heavier than other parts, and material deflection is objectionable for other reasons.

In those instances where embossed type characters have been provided on printing devices of the character that are sequentially passed through printing machines of the kind to which this invention pertains, the type characters are customarily arranged in rows that extend across the devices transversely to the line of movement thereof through the machines. Moreover, where roller platens have been employed for making impressions from type characters arranged in

this manner, the axes of the roller platens have extended in substantially parallel relation with the extent of the rows of type characters. Frequently the rows of type characters afford an arrangement from which a name, street and number, city and state or the like constituting an address may be printed and it will be appreciated that in such an arrangement the length of various rows of type characters will vary. For example, the name may be relatively short, the street and number may be relatively long, and the city and state may be of a length intermediate the length of the name and the length of the street and number and, of course, other wide variations in the lengths of the lines may occur. Thus, particularly where a roller platen is employed for making impressions of the type characters so arranged and the roller is caused to move across the devices so as to advance from one line to another, there may be a tendency for the roller platen to make heavy impressions from short lines and lighter impressions from long lines of type characters. Such tendency, however, may be overcome by so arranging the machine parts entailed in making the impressions that material deflection therein is prevented.

In view of the foregoing it will be appreciated that it is essential that the machine parts, entailed in making impressions from printing devices of the character sequentially fed through printing machines, be so arranged that material deflection in the parts in the course of impression operations in the machine will be avoided and an important object of this invention is to so arrange the parts operative to make impressions from printing devices in printing machines that objectionable deflection therein in the course of impression operations will be prevented.

Sufficient rigidity so as to avoid objectionable deflection may of course be imparted by forming the parts to include sufficient material to resist objectionable deflection but where castings, forgings or conventional structural sections have been employed for this purpose, it has been necessary to make the parts quite heavy and this has been objectionable because it is advantageous to have printing machines of the aforesaid character as light in weight as is consistent with efficient operation and the use of relatively heavy sections is objectionable from a cost standpoint and for other and kindred reasons.

Thus, still another important object of this invention is to so arrange the parts entailed in the performance of impression operations in printing machines that objectionable deflection in such parts in the course of impression operations effected thereby will be prevented but at the same time to construct such parts so as to be as light as will be possible consistent with efficient and proper operation.

It has been mentioned hereinabove that it is objectionable to transmit the forces attendant to impression operations in printing machines of the aforesaid character through the frames of such machines and in view of this it is another object of this invention to so arrange the parts entailed in the performance of impression operations in printing machines that the stresses attendant to the performance of such operations will not be transmitted through the frame of the machine in which the impression operations are effected and an object ancillary to the foregoing is to arrange the support on which the printing devices rest during impression operations, and the means for applying the impression producing

pressure, in a unitary member in which all the forces attendant to the performance of impression operations will be absorbed and dissipated.

More specifically it is an object of this invention to support an anvil on which the printing devices may rest while impression operations are performed thereon in a unitary structure, also affording a support for the platen or other member employed for applying the impression pressure.

While it is essential that such deflection as might impair the production of clear cut and otherwise satisfactory impressions in the parts entailed in the performance of impression operations in printing machines be avoided, it is at the same time desirable that some deflection be afforded so as to compensate for variations in the thicknesses of sheets or the like on which the impressions are made and thus yet another important object of this invention is to prevent such deflection in the parts entailed in the performance of impression operations in printing machines as may impair the production of satisfactory impressions and yet at the same time afford as much deflection as may be required to afford such compensation, for variations that may be encountered, as may be needed.

In order that the foregoing and other and kindred objects of this invention may be realized, I utilize sheet metal plates and I so form, arrange and join these plates that supports for both an anvil or the like and a platen or other pressure member are afforded in the unitary structure made from such plates.

Thus, still another object of my invention is to so form, arrange and join metallic plates that the stresses attendant to the performance of impression and other operations by parts carried thereby will be absorbed and dissipated therein without objectionable deflection of the supports for the parts entailed in the performance of such operations and an object related to the foregoing is to weld together metal plates formed and arranged in a selected manner so as to thereby afford a novel unitary structural section.

While the present invention is particularly useful in printing and like machines, it is to be understood that the structural section to which this invention primarily pertains will be useful in other machines such as, for example, punching machines and presses and in other instances where it is necessary to dissipate stresses attendant to the production of opposing forces and thus while the present invention is described with particular relation to printing machines of the character through which printing devices are sequentially fed, it is to be understood that while this is the preferred it is not the sole embodiment of the present invention and that therefore the invention is not to be considered as being limited to use in printing machines of the aforesaid character.

Other and further objects are to so form metal plates that, when such plates are joined into a unitary structure, maximum resistance to deflection will be afforded; to so form plates, as aforesaid, that interconnection along abutting edges thereof may be effected by welding the plates together to afford a unitary structure; to so incorporate an anvil or the like and a platen arrangement or the like in a unitary structure that what may be called a printing frame will be afforded; to so form and relate the metal plates of such a printing frame that bearing means for operating shafts for operative parts

may be extended therethrough without reducing the structural rigidity of the frame; and to so form and relate the metal plates of such a structure that the assembly and welding operations may be readily and easily performed and efficiently inspected upon completion of the frame.

Other and further objects of the present invention will be apparent from the following description and claims and are illustrated in the accompanying drawings which, by way of illustration, show a preferred embodiment and the principle thereof and what I now consider to be the best mode in which I have contemplated applying that principle. Other embodiments of the invention embodying the same or equivalent principle may be used and structural changes may be made as desired by those skilled in the art without departing from the present invention and the purview of the appended claims.

Fig. 40 is a top plan view of the novel platen arm of this invention showing the manner in which the parts are welded together;

Fig. 41 is a side elevation of the parts as shown in Fig. 40;

Fig. 42 is an end view looking in at the right-hand end of Fig. 41; and

Fig. 43 is a fragmentary plan view taken substantially on the line 43—43 on Fig. 41.

The machine illustrated in the accompanying drawings in which the novel printing frame of this invention is utilized is described in detail in my co-pending application, Serial No. 388,998, filed April 17, 1941, and reference may be made to this application for a detailed description of the various operative parts of the machine. Briefly, however, this machine includes a table top T on which sheets such as envelopes, letter-heads, bill forms, ledger sheets and the like may be arranged to receive impressions from printing devices or the like sequentially fed through the machine, the devices being introduced into the magazine M and being successively withdrawn from the bottom of the stack thereof in the magazine by the arrangement described in detail in my co-pending application, the printing devices being advanced through the machine in a step-by-step manner and in the course of such movement coming to rest in operative relation with the platen P to have one or more impressions made therefrom upon operation of the platen. At the time the printing devices come to rest in operative relation with the platen P, they are disposed on an anvil A which, along with the platen P, is carried by the novel printing frame of this invention.

The platen P is preferably a so-called roller platen and while this platen may be operated in a wide variety of ways, an advantageous way of so operating this platen is described in full detail in my co-pending application, Serial No. 361,530 filed October 17, 1940. In the present instance, however, the platen P is carried by a carriage C having supporting and guiding rollers 50 thereon which travel on tracks 52 provided on the carriage support plate 53 adjustably connected to the platen head forging 54, described more fully hereinafter. The carriage plate 53 is connected to the head 54 for vertical adjustment movement which is effected by an adjusting knob 55, and by rotation of the knob 55 it is possible to vary the pressure exerted by the platen P in the course of rotation thereof. The particular manner in which this adjustable interconnection is afforded is described in full de-

tail in my aforesaid co-pending application, Ser. No. 361,530, this adjustability also enabling the platen P to be adjusted relative to the printing devices which come to rest on the anvil A so as to insure that the platen will uniformly cooperate with type characters afforded on the printing devices so as to produce uniform impressions.

In the course of operation of the machine, the shaft 60 is set in operation and through the intermediary of an eccentric 61 thereon is operative through the adjustable link 62 to rock the arm 63 fast on a shaft 64 mounted in a manner described in further detail hereinafter. The shaft 64 also has an arm 65 thereon at the end thereof opposite that at which the arm 63 is mounted, and a link 66 is pivotally connected to the free end of the arm 65, the opposite end of this link being pivotally connected to the free end of an arm 67 fast on a shaft 68 mounted in a manner described in further detail hereinafter. At the end of the shaft 68 opposite that at which the arm 67 is fast, there is an arm 69. The arm 69 has a transverse pin fixed therein at its free end through which an operative connection is provided to the platen carriage C. Hence, in the course of operation of the shaft 60, a reciprocatory movement along the platen support 53 is imparted to the carriage C. In the course of this reciprocatory movement means described in detail in my aforesaid co-pending application, Ser. No. 361,530 are effective through the toggle 71 to lower the platen P into operative relation with the printing device resting on the anvil A, and in the course of reciprocation of the carriage C, after the platen P has been lowered into operative relation with a printing device, an impression is made from the type characters on the printing device onto a sheet disposed beneath the platen P, an ink ribbon (not shown) being interposed between type characters on the printing device and said sheet.

The printing frame 100, which is the novel structural section to which this invention primarily pertains and one which the anvil A and the platen P are mounted, is mounted on the main supporting frame 101 of the printing machine, which main frame also carries the table top T. As shown in Fig. 1, the printing frame 100 is associated with the rectangular table top T so as to extend diagonally with respect thereto. The frame 101 is formed to provide a pair of supporting rails 102 and 103 that extend parallel to the front edge of the table top T, these supporting rails being employed in mounting certain of the operative parts of the printing machine and also serving as the support for the printing frame 100.

The printing frame 100 is of a generally C-shaped configuration and includes an upper arm or section 105 and a lower arm or section 106 which project in a generally parallel relation from a vertical portion 107 of the printing frame extends through the table top T adjacent the right rear corner thereof, as shown in Fig. 1, so that the upper arm 105 extends diagonally across the table top T in upwardly spaced relation with respect to the table top, while the lower arm 106 extends beneath the table top T and in the complete machine is concealed and housed within the frame 101.

In the course of operation of the machine, the force required to effect the desired printing operation is applied between the anvil A and the head forging 54 through the extension of the

toggle mechanism 71 of the platen, and this force is so applied that the tendency is to separate the opposed arms 105 and 106 of the printing frame 100. The printing frame 100 is therefore constructed to resist such separating effect of the force which is thus applied between its arms 105 and 106, but at the same time, I have so formed the printing frame that it has a pleasing appearance suitable for incorporation in a printing machine of the character herein and also as to avoid the necessity for further housing or concealing of unsightly parts.

In attaining the foregoing, the printing frame 100 is constructed from a plurality of independently formed parts most of which are made from sheet metal or sheet steel stock, these independently formed parts being thereafter assembled and then secured in the desired rigid relationship by welding. The desired rigidity is also in some instances assured by mechanical interlocking of these separately formed elements.

The several separately formed elements which enter into the production of the printing frame 100 are shown in an exploded relationship in Fig. 10 of the drawings, the parts being shown in this view in such a way as to indicate the relationship therebetween in the completed printing frame 100. Thus, as shown in Fig. 10, a central plate 110 is provided, which is generally C-shaped in form so as to provide an upper arm 115 and a lower arm 116 connected by an integral intermediate vertical portion 117. This central plate 110 is adapted to be enclosed within or between two shell-like members 120 and 130 which are adapted to be placed on opposite sides of the central plate 110 with the edges of the shell-like members 120 and 130 substantially registered with the bordering edges of the central plate 110.

The shell-like member 120, which will hereinafter be termed the left-hand shell member, has an upper arm 125, a lower arm 126 and an intermediate vertically extending connecting portion 127. The arms 125 and 126 and the vertical portion 127 of the shell-like member 120 are generally channel-like in cross section, as will be seen from a comparison of Figs. 5, 10 and 31, this channel-like form being such that the width of the channel, that is, the width of the web thereof, varies in the extent of the arm 125 so as to be considerably wider at the rear end of the arm 125. Similarly the web of this channel is relatively wide as it extends through the length of the vertical portion 127 of the shell-like member 120 and the width thereof gradually decreases from the rear end of the arm 126 toward the forward end thereof. Thus, the channel-like form of the arm 125 is provided by a web portion 125W having upper and lower flanges 125' and 125" extending from the upper and lower edges of the web 125W. As shown in Figs. 5 and 31, the flanges 125' and 125" diverge slightly so that the open face defined by the edges of the flanges 125' and 125" is at all points along the arm 125 slightly greater in width or vertical dimension than is the web 125 at the corresponding point along the arm.

At the rear end of the arm 125, the web 125W merges with an integral web 127W of the vertical portion 127, and the rear portion of the upper flange 125' merges with a flange 127' which forms the rear flange of the vertically extending portion 127. The two flanges 125' and 127' are preferably merged through a curved rear corner, as indicated at 140.

The lower arm 126 is similarly formed with a web 126W which merges integrally with the lower end of the vertically extending web 127W, and a similar channel-like form is provided by a lower flange 126' which merges integrally through a rounded corner portion 141 with the rear flange 127'. A similar upper flange 126" is formed along the upper edge of the web 126W, and the flanges 125" and 126" are connected by an integral flange 127" formed along the forward edge of the web 127W.

The right-hand shell-like member 130 has an upper arm 135 and a lower arm 136 connected at their rear ends by an integrally formed vertically extending portion 137. The two arms 135 and 136 and the vertically extending portion 137 are of a channel-like form generally similar to the form of the shell-like member 120. The arm 135 has a web 135W with upper and lower flanges 135' and 135" along its upper and lower edges, respectively. The vertically extending portion 137 has a web 137W with a rear flange 137', as best shown in Fig. 6 of the drawings, and a forward flange 137" along its forward edge. The lower arm 136 has a web 136W with upper and lower flanges 136" and 136' formed thereon, and it will be noted that these various flanges of the member 130 merge through rounded corners in much the same manner as has been described in connection with the shell-like member 120.

The upper and lower arms 105 and 106 of the printing frame 100 are so formed that the head forging 54 and the anvil A may be associated therewith in a mechanically interlocked relationship, thereby to assist in properly transmitting the impression making forces from the head forging 54 and the anvil A to the upper and lower arms respectively of the printing frame 100. This interlocked relationship is in the present instance attained by forming interlocking means in each of the three principal structural elements of the arms 105 and 106, and the formation of this interlocking means is shown in detail in Figs. 32 to 39 of the drawings.

The interlocking means of the upper arm 105 is arranged to interlock with a plate-like tongue 150 which extends rearwardly as an integral portion of the head forging 54. The tongue 150 is generally rectangular in form and is arranged to extend into notches formed in the webs 125W and 135W and in the arm 115 of the central plate 110. The notching of these various elements of the upper arm 105 varies somewhat as between the several elements, this variation in the present instance being provided by reason of the angular relationship of the printing frame 100 with respect to the rectangular top T of the printing machine. Thus, as shown in Figs. 1 and 8 of the drawings, the platen carriage C moves along the path which extends from front to rear of the machine and the lower face of the head forging 54 is so formed as to provide clearance for the mounting of the carriage plate 53. Thus, as shown in Figs. 10, 32 and 33, the forward end of the lower flange 125' is cut off at an angle to provide an edge 151 which, in the final positioning of the printing frame 100, is located parallel to the path of movement of the platen carriage C. At the juncture of this edge 151 with the web 125W, the web 125W is cut away along a generally vertical line 152 toward the center of the web 125W to such a point as to merge with a slot 153 which is cut inwardly or rearwardly from the end of the web 125W. Thus,

the left-hand edge portion of the tongue 150 may be inserted into the slot 153 so as to interlock with that portion of the slot which is located to the right of the vertical line 152 in Fig. 33, and, in this relationship, clearance is provided so that the carriage plate 53 may extend rearwardly beneath at least a portion of the upper arm 105.

The tongue 150 is also interlocked with a notch 155 formed in the upper arm 115 of the central plate 110, and below the notch 155 the forward end of the arm 115 is cut away to form a rearwardly spaced forward edge 156, thereby to provide clearance for the carriage plate 53 as hereinbefore described in connection with the edge 151. The tongue 150 is also interlocked with the arm 135 of the right-hand shell-like member 130, which, as shown in Figs. 10, 36 and 37, has an elongated slot or notch 157 formed therein so as to extend rearwardly of the forward end thereof.

When the head forging 54 is positioned in its final interlocked relationship upon the ends of the various members which make up the upper arm 105, integral portions of the head forging are arranged to close the forward end of the arm 105, and this function or relationship is attained through the form of the head forging 54 which is shown in detail in Figs. 19 to 28, inclusive, of the drawings. As shown in Figs. 1, 8 and 19, it will be observed that the head forging 54, when the printing frame is mounted in operative position, has a forward edge 160 which is parallel to the forward edge of the table top T, and that it has right and left-hand side edges 161 and 162 which extend rearwardly perpendicular to the forward edge 160. At the rear end of the edge 161, the tongue 150 extends at an angle which corresponds to the angular positioning of the printing frame 100 on the main frame 101. This tongue 150 is generally rectangular in form and has a bordering rib 163 along the edge which merges with the edge 161, this rib 163 merging with a rib 164 which extends along the rear end edge of the tongue 150, and there being a similar rib 165 along the other edge of the tongue 150 parallel to the rib 163. Along the center line of the tongue 150 and parallel to the ribs 163 and 165, a similar rib 166 is provided, and in most of its other portions the tongue 150 comprises a relatively thin web portion 167, as shown in Fig. 25. This web portion 167 is spaced substantially midway between the upper and lower edges of the various ribs 163, 164, 165 and 166.

The upper surface of the head forging 54 is also provided with an upwardly extending flange 170 which defines the border between the tongue 150 and the balance or forward portion of the head forging. This flange 170 has sloping upper surfaces 170' and 170", as shown in Figs. 20 and 22, so that the flange 170 will, in the completed printing frame, fit against the end edges of the arms 115, 125 and 135 with the surfaces 170' and 170" forming smooth continuations of the outer surfaces of the flanges 125' and 135', respectively. The flange 170 is similarly formed with end edges 171, and the ends of the webs 125W and 135W abut against the rear surface of the flange 170 so that the end surfaces 171 form smooth continuations of the outer surfaces of these webs.

It will be noted that the side and end edges of the tongue 150 are formed with a slight angle or draft on opposite sides of the horizontal center line thereof, as indicated at 172 in Figs. 20 and 31 and the webs 125W and 135W are preferably

formed with a corresponding angular form so as to form continuations of the side draft surfaces 172, as shown in Fig. 31. This angular formation of the webs 125W and 135W facilitates the manufacture of the printing frame 100, and preferably the angular formation of the two webs is terminated so as to merge with the flat portions of the web relatively close to the rear ends of the interlocking slots 153 and 157. The up-standing flange 170 also functions in imparting strength and rigidity to that portion of the head forging which projects outwardly beyond the end of the sheet metal portion of the arm 105, this function being attained by a relatively high stiffening rib 175 which projects rearwardly from the flange 170 relatively close and parallel to the rib 165 and a forwardly projecting stiffening rib 176 which extends from the flange 170 along the upper surface of the head forging 54. The stiffening rib 176 tapers gradually downwardly in a forward direction, as shown in Figs. 20, 26 and 28, and in order to facilitate machining of the forging for the mounting of certain operative parts thereon, the stiffening rib 176 is, in the present instance, made of a sinuous form, as shown in Fig. 19.

As hereinbefore pointed out, the platen carriage C must move along a path perpendicular to the forward edge 160 of the head forging, and the lower or bottom face of the head forging is so formed as to provide clearance for the various parts which are required in attaining such reciprocation of the platen carriage C. This formation of the lower surface of the head forging 54 is attained in such a manner as to close the lower half of the forward end of the upper arm 105. Thus, as shown in Fig. 21, the lower face or surface of the tongue 150 has a flange 180 formed thereon in such a relation as to form a continuation of the side 161 of the head forging, and when the head forging 54 is positioned on the arm 105 with the tongue 150 thereof interlocked with the notches of the several elements of the arm, this flange 180 engages the forward end edges of the two arms 125 and 135. Thus, when the tongue 150 is placed in its final position with respect to the sheet metal elements of the arm 105, the upper edge of the slot 153 lies along the upper edge of the rib 165 of the tongue 150 with the end edge of the slot 153 abutting the end of the tongue 150 and the lower edge of the slot 153 extending along the lower edge of the rib 150 to the adjacent right-hand face of the downwardly projecting rib 180. The end edge 152 (Fig. 33) extends downwardly along and in abutment with the face of the flange 180 toward the lower extremity of the flange, while the edge 151 of the flange 125' extends along the adjacent face of the flange 180 adjacent the lower edge thereof. This relationship may be most readily understood from an examination of Fig. 10 of the drawings.

Adjacent its other or forward end, the flange 180 is engaged by the web 135W of the arm 135, and this engagement is continued downwardly along the web 135W and throughout the width of the lower flange 135''. This engagement is provided by an angularly cut end edge 181 formed on the lower flange 135'', as indicated in Fig. 36 of the drawings.

The head forging 54 is also formed on its lower surface so as to partially enclose the carriage plate 53 and so as to fully enclose the mechanism for vertically adjusting and leveling the carriage plate. The forward edge 160 therefore has a

downwardly projecting skirt portion 160' and the side edge 161 is formed with a downwardly projecting skirt portion 161', while the edge 162 has a downwardly projecting skirt portion 162'. These downwardly projecting skirt portions are formed integrally with each other and are best shown in Figs. 21 and 29, which are bottom plan views of the head forging 54. It will be noted in Fig. 21 that the skirt portion 161' forms a continuation of the downwardly projecting flange 180. The skirt 161 is provided on its inner surface with a boss portion 185, as shown in Figs. 21, 27 and 30, and in the finished machine the boss 185 is bored so as to provide a bearing for the shaft upon which the adjusting knob 55 is mounted.

Other machining operations are performed, as will hereinafter be described, on the projecting portion of the head forging 54, as illustrated in Figs. 8 and 29, and in the finished machine certain portions of the adjusting and leveling mechanism of the carriage plate 53 are exposed on the upper surface of the head forging 54, as illustrated in Figs. 8 and 29. The particular construction and arrangement of these exposed operating elements are described in my aforementioned co-pending application, Ser. No. 361,530, filed October 17, 1940. These operative parts are, however, concealed in the finished machine by a cover plate 186 which is positioned on the top of the head forging 54, as shown in Figs. 1, 2 and 3. This cover plate 186 is positioned on the top of the head forging by means of a downwardly opening socket or bore 187, formed in the inner surface of the cover plate 186, which engages with an upstanding pin 188 carried on the upper face of the head forging 54, as shown in Fig. 2. The exposed outer surfaces of the cover plate are preferably disposed in the angular relation indicated at 189, thereby to form continuations of the outer upper surfaces of the upper arm 105. These surfaces 189 are then tapered downwardly so as to provide a pleasing cooperating form with respect to the downwardly and outwardly sloping faces of the edges 160, 161 and 162 and the associated skirt portions.

Before proceeding with the description of the actual assembly of the printing frame 100, the various elements of the lower portion of the arm 106 will be described in detail. By reference to Fig. 3 of the drawings, it will be observed that the anvil A comprises a separately formed and separately mounted structure which may be of many different forms, and this anvil A is located directly over an anvil supporting plate 190 which is permanently mounted upon the lower arm 106 of the printing frame 100. The anvil A is so arranged that the downward force applied thereto in the course of a printing operation is transmitted directly to the anvil supporting plate 190.

The anvil supporting plate 190 comprises an elongated rectangular block of bar stock which rests upon and is mechanically interlocked with the various elements of the lower arm 106 so as to effectively transmit the downwardly applied forces to the structural elements of the arm 106. In providing for such an interlocked connection of the anvil supporting plate 190 with the arm 106, a vertically positioned plate 191 is provided which underlies the forward edge of the anvil supporting plate 190, as shown in Fig. 3. This plate 191 also functions in imparting strength or stiffness to the anvil supporting plate 190, as well as in the mounting of the printing frame 100 in

the main frame 101. In the final assembled relationship of the parts, the anvil supporting plate 190 is associated and interlocked with the lower arm 106, as shown in Figs. 3 and 6, and to provide for such association the several structural elements of the arm 106 have their ends formed in the manner which is shown in detail in Figs. 10, 34, 35, 38 and 39. Thus the arm 126 of the left-hand shell member 120 has the upper edge of its web 126W cut downwardly or slotted downwardly, as indicated at 193, so that the anvil supporting plate 190 may rest upon this edge 193 with its rear edge in abutment with an angularly formed end edge 194 formed on the upper web 126''. This end edge 194 extends downwardly along the web 126W to the level of the edge 193, as shown in Figs. 10 and 35.

The forward upper edge of the arm 116 of the central plate 110 also has a notch 195 formed therein so that the anvil supporting plate may rest in the notch 195 with its rear edge in abutment with the shoulder 195' formed by the rear edge of the notch 195, as indicated in Fig. 10 of the drawings.

The right-hand shell member 130 also has its lower arm 136 formed to support and engage the anvil supporting plate 190. This formation is best shown in Figs. 10, 38 and 39 wherein it will be evident that the upper flange 136'' of the arm 136 has a notch formed therein which provides one angular surface 196 which engages the rear edge of the anvil supporting plate 190 and another end edge surface 197 which may engage with the right-hand end edge of the anvil supporting plate 190. This edge 197 continues downwardly into the web 136W of the arm 136 which is properly notched to provide a horizontal surface 198 upon which the anvil supporting plate 190 may rest.

Beneath the anvil supporting plate 190, the end of the arm 106 is closed by an angle plate 200, shown in Figs. 5 and 10 to 14, inclusive, and this angle plate 200 serves the additional function of distributing the stresses applied by the plate 190 among the three members 110, 120 and 130 of the printing frame 100. The angle plate 200 is arranged so that its right-hand end edge, as seen in Figs. 6 and 10, abuts the inner face of the web 136W while its lower edge extends along the upper edges of the lower flanges 136' and 126', and it will be noted, in Figs. 10 and 34 of the drawings, that the end edge of the lower flange 126' terminates along an angle, as indicated at 201, this angular edge 201 being parallel and spaced somewhat forwardly of the edge 194 of the upper flange 126''. This angular edge 201 merges with an edge 202 formed parallel to the web 126W, this edge 202 being spaced from the juncture of the flange 126' and the web 126W so that a rounded edge is provided on that portion of the web 126W which extends forwardly beneath the anvil supporting plate 190.

In the assembly of the printing frame of the present invention, the head forging 54 and the angle plate 200 are first secured to or mounted upon the central plate 110 and the first sub-assembly which is thus formed is illustrated in Figs. 11 to 14, inclusive, of the drawings. Thus the angle plate 200 is placed in abutment with the end of the arm 116, the end of the arm 116 being positioned against the angle of the plate 200. The positioning of the parts is such that the upper surface of the angle plate 200 is flush with the surface of the notch 195 so that the notch 75

195 and the upper surfaces of the angle plate 200 lie in a plane and will serve to afford support to the anvil supporting plate 190 throughout a substantial and relatively extended area of the lower surface of the plate 190. While secured in this position by a suitable fixture, the arm 116 and the angle plate 200 are fastened in rigid relation by welding, which is herein indicated as two tack welded areas 205 adjacent the upper and lower edges of the angle plate 200, as shown in Figs. 12 and 13.

The head forging 54 is then placed in the desired relationship to the center plate 110, and it will be noted that the slot 155 in the central plate has a relatively snug fit with respect to the upper and lower surfaces of the central rib 166 of the tongue 150. The rib 166 is of a width which is somewhat greater than the thickness of the central plate 110 so that on opposite sides of the plate, corners are provided in which the desired welded joints may be formed. Such welded joints are provided between the arm 115 and the rib 166 along opposite sides of the arm 115 and along the upper and lower edges of the slot 153 and, as shown in Figs. 12, 30 and 31, this is accomplished by tack welding at a plurality of points, as indicated at 208. It will be observed in Fig. 10 of the drawings that the arm 115 below the slot 155 has an end edge 156 which is adapted to abut the downward flange 180 of the head forging and, as shown in Figs. 12 and 30, this end edge 156 is secured as by tack welding at 209 to the flange 180. Above the slot 155 the arm 115 has an end edge 156' which abuts the sloping rear face of the upwardly extending flange 170, and this end edge is fixed to the flange 170 by tack welding, as indicated at 210 in Figs. 12 and 30.

Such welding of the head forging 54 and the angle plate 200 to the central plate 110 provides a first sub-assembly, which is illustrated in detail in Figs. 11 to 14, and, inclusive, after completion of this first sub-assembly, the two shell-like side members 120 and 130 are placed in position on opposite sides of the central plate 110 and, after being clamped rigidly in the desired position or relation by means of a suitable fixture, are fixedly secured in place upon the first sub-assembly so as to form a further completed or second sub-assembly, which is illustrated in detail in Figs. 40 to 43, inclusive. When the parts are thus positioned, the edges of the outer flanges 125', 127' and 126' of the left-hand shell member 120 abut the left-hand face of the central plate 110 adjacent the outer edge thereof, while the edges of the inner flanges 125'', 127'' and 126'' of the left-hand shell member 120 abut the left-hand face of the central plate 110 adjacent its inner edge. Similarly, the edges of the outer flanges 135', 137' and 136' of the right-hand shell member 130 abut the right-hand face of the central plate 110 adjacent the outer edge thereof, while the inner flanges 135'', 137'' and 136'' abut the right-hand face of the central plate 110 adjacent the inner edge thereof. The register of the several flanges of the members 120 and 130 with the edges of the central plate 110 is such that a shallow groove is formed about the inner and outer sides of the assembly for the purpose of facilitating the formation of a strong and neat welded joint between the parts. In each instance this groove is so arranged that the bottom of the groove is formed by an edge of the central plate 110, while the sides of the groove are formed by the edges of the flanges of the mem-

bers 120 and 130, this form and relationship being shown in detail in Figs. 5, 6, 16 and 31.

With the parts thus positioned, the outer flanges of the two shell members 120 and 130 are rigidly secured to the central plate 110 by welding as at 215, while the inner flanges of the two shell members are welded to the central plate 110 as at 216. These welding operations serve to fill the grooves with metal which is fused to the flanges and the central plate 110, and preferably sufficient metal is deposited in the welding operation to provide for subsequent grinding of each of said welded joints to provide a smooth rounded outer surface across the welded joint and merging with the outer surfaces of the flanges. In practice it has been found that these welded joints after such a grinding operation provide a continuous and smooth surface which does not disclose the manner in which the flanges have been joined.

In the second sub-assembly of Figs. 40 to 43, the end of the web 136W abuts the rear face of the angle plate 200 and a rigid welded joint is formed therebetween, as indicated at 217 in Figs. 41 and 43. The lower edge of the angle plate 200 is arranged so that its lower rear corner 201 registers with the upper rear corner of the end of the flange 136' and with the edge 201 of flange 126', while the left-hand end of the angle plate 200 overlies the ledge portion of the flange 126' just beyond the left-hand end of the edge 201. This relationship is such as to provide an angular groove between the bottom of the angle plate 200 and the end edges of the flanges 126' and 136', and a welded joint is formed therewith, as indicated at 218 in Fig. 18. The left-hand end of the angle plate 200 abuts the web 126W of the arm 126, as shown in Figs. 41 and 43, and a welded joint is formed along this line of abutment, as indicated at 219.

The head forging 54, in the second sub-assembly shown in Figs. 40 to 42, is welded continuously about its points or lines of contact with the end edges of the two side members 120 and 130. Thus, the two upper flanges 125' and 135' abut the rear face of the flange 170 of the head forging 54 and are welded thereto, as indicated at 220. The end edges of the webs 125W and 135W also abut the rear surface of the upstanding flange 170 of the head forging and are welded thereto, as indicated at 221 in Fig. 41.

The slot or notch 157 of the right-hand shell member 130 embraces the rib 163 so as to leave a V-shaped groove therebetween in which a weld is formed, as indicated at 222 in Figs. 31 and 41. Beneath the slot 157, the end edge of the web 135W abuts the downwardly extending flange 180 of the head portion and is welded thereto as indicated at 223 in Fig. 41. The angularly extending edge 181 (Fig. 36) abuts the downwardly extending flange 180 adjacent its lower edge and a welded joint is similarly formed along this juncture.

The end edge of the web 125W abuts the rear face of the flange 170 and is welded thereto in the same manner, while the edges and ends of the slot 153 are welded as at 222' to the rib 165 in the same manner as the welding operation about the rib 163. Below the slot 153 the edge 152 of the web 125W abuts the downwardly extending flange 180 and is welded thereto while the angular edge 151 of the lower or inner flange 125' abuts the downwardly projecting flange 180 adjacent its lower edge and is welded thereto. The welding of the flanges 125' and 135' provides a

continuous joint between these flanges and the lower edge of the downwardly projecting flange 180 and after grinding of the welded joints, a smooth and continuous surface is formed from the flanges 125' and 135' across the lower edge of the depending flange 180 so that the joint therebetween is practically imperceptible, as indicated in Fig. 29.

After the welding of the head forging 54 to the shells 120 and 130 has been completed, the anvil supporting plate 190 and the vertical plate 191 are secured in position on the formed end of the lower arm 106, and since the plate 191 serves as a part of the mounting means for supporting and positioning the printing frame 100 on the machine frame 101, and must cooperate with means located on the rear portion of the printing frame 100 in accomplishing this supporting and positioning function, the securing of the plates 190 and 191 on the printing frame is correlated with the mounting of a supporting and positioning bracket 230 on the rear portion of the printing frame. This rear bracket 230 is, in the present instance, secured upon the outer or rear flange 127' of the left-hand shell member 120, as shown in Figs. 6 and 9, and in the present instance this bracket is of a U-shaped form having an upper arm 230' and a lower arm 230'' both projecting in a rearward direction. The upper arm 230' acts as a support for a portion of the table top T, while the lower arm 230'' rests upon the rear supporting rail 103 and is secured thereto by a pair of headed screws 232.

The second sub-assembly of Figs. 40 to 42 is therefore clamped in a suitable fixture with the bracket 230 and the plates 190 and 191 in the desired relation thereto, and the bracket 230 is welded to the flange 127' along its vertical or side edges, as indicated at 233 in Figs. 6 and 9, and is also welded along its upper and lower edges as indicated at 234 in Fig. 3.

The edges 193 and 194 of the left-hand lower arm 126 are welded to the bottom and rear surfaces of the plate 190, as indicated at 235 and 236, respectively, in Fig. 17 of the drawings. The edges 196 and 197 of the lower arm of the right-hand shell member 130 are welded to the rear and right-hand end surfaces of the plate 190, as indicated at 237 and 238, respectively, in Fig. 15. The edge 198 of the web 136W is welded to the lower surface of the plate 190, while the end of the web 136W is engaged with and welded to the rear surface of the plate 191, as indicated at 240 in Fig. 18. It will also be observed that the web 126W extends into engagement with the rear face of the plate 191, and a welded joint is formed therebetween, as indicated at 241 in Figs. 15, 16 and 18. Preferably, the upper rear edge of the plate 190 is rigidly secured to the platen supporting plate 190 by a series of tack welds 243, shown in Figs. 3 and 18.

After the anvil supporting structure and the rear bracket 230 have been secured in position, means is preferably mounted on the printing frame 100 to provide for the support of a plurality of operating shafts therein, but it must be recognized that in certain applications of the present printing arm, one or more of these shaft supporting devices may be eliminated. In the machine for which the herein described printing frame 100 is particularly adapted, the shafts 64 and 68 are arranged to extend through bearings provided in the printing frame, and in addition to these shafts an additional operating shaft 250 (Fig. 3) also extends through the printing frame.

Thus, as illustrated in Figs. 4, 5 and 8, the present printing frame 100 is provided with three bearing supporting tubes 251, 252 and 253 which extend through and are rigidly secured in the printing frame. In the present instance these shafts are parallel to each other and parallel to the forward edge of the table top T so that a plurality of elliptical openings are formed in the central plate 110 and in the webs of the shell-like side members 120 and 130 so that the several bearing supporting tubes may extend therethrough in the proper angular relationship to the central plate and the webs. To receive the upper bearing supporting tube 251 which is to support the shaft 68, the web 125W has an opening 254 formed therein, the arm 115 of the central plate 110 has an opening 255 therein, while the web 135W has an opening 256 therein. Similarly, the web 126W, the arm 116 and the web 136W have elliptical openings 257, 258 and 259, respectively, formed therein to receive the bearing supporting tube 252 which is to support the shaft 64. The web 126W, the arm 116 and the web 136W also have elliptical openings 260, 261 and 262, respectively, formed therein to receive the bearing supporting tube 253 which is to support the shaft 250. The position and relationship of these elliptical openings are clearly indicated in Figs. 10, 12 and 41.

The several bearing supporting tubes 251, 252 and 253 are inserted through the appropriate openings and are welded, as indicated at 263 and 264 to the webs 126W and 136W, respectively, the welds 263 and 264 in each instance extending entirely and continuously about the periphery of the tubes. Since the left-hand of the bearing supporting tube 253 projects for a considerable distance beyond the left-hand side of the printing frame 100, as shown in Figs. 6 and 8, a triangular bracing web 265 is interposed in substantially a horizontal plane between the left-hand side of the lower arm 106 and the bearing supporting tube 253. This bracing web 265 is welded to the bearing supporting tube 253 and to the left-hand side of the arm 106. The projecting left-hand end of the bearing supporting tube 251 is also braced by a triangular supporting web 266, this supporting web 266 having one edge welded to the web 125W, as indicated at 267 in Fig. 5, and having a down-turned flange 268 along its rear edge which is welded as indicated at 269 to the upper face of the bearing supporting tube 251. This downwardly extending flange 268 continues along the left-hand edge of the web 266, as indicated at 270 in Fig. 8, and this continuation 270 extends downwardly for a considerable distance, as indicated in Fig. 3, so as to provide an enclosing housing for certain control mechanism which may in some instances be associated with platen P and which is described and claimed in my said copending application, Ser. No. 361,530, filed October 17, 1940. The flange 270 is arcuately slotted along its rear edge, as indicated at 271 in Fig. 3, and this arcuately slotted portion is welded to the tube 251. At its forward edge the flange 270 abuts the web 125W and is welded thereto as indicated at 272 in Fig. 8. Since the operative mechanism which is to be housed within the flange 270 and the web 266 is of such a character as to require an operating connection extending through the flange 270, a removable plate 273 is secured thereto as by screws 274 so as to conceal an opening which is provided in the flange 270 and which is used only when such operative mechanism is employed.

within the enclosure provided by the flange 270.

After the various bearing supporting tubes have been thus mounted and welded into position on the printing frame 100, the printing frame is in condition for the performance of the various machining operations which are required thereon. The first machining operation is performed on the forward face of the plate 191 and the lower forward corner of the plate 190 so as to provide surfaces for engagement with the rear surface and top surface of the forward supporting rail 102. The top surface of the anvil supporting plate 190 is then machined and the arcuate groove 280 is formed therein which functions in the mounting of the anvil A upon the plate 190. The rear bracket 230 is then machined so as to properly form and locate the upper surface of the arm 230' and the lower surface of the arm 230''. A plurality of holes 281 are then bored in the plate 191 so that the plate 191 may be bolted in the desired relation to the supporting rail 102. Similarly, holes 283 are bored in the lower arm 230' of the rear bracket 230 so that this bracket may be secured in place on the rail 103 by means of the headed studs 232. After the positioning surfaces and securing bores have been thus formed, the printing frame 100 may be secured in predetermined fixed relation in a suitable fixture for the performance of the required boring operations upon the head forging 54, such boring operating being required to provide for the mounting of the leveling and adjustment means for the carriage support plate 53, this adjusting and leveling means being described in detail and claimed in my aforesaid co-pending application Ser. No. 361,530, filed October 17, 1940.

While the printing frame is thus secured in a rigid and predetermined relation, the opposite ends of each of the bearing supporting tubes are counterbored as shown in detail in Fig. 7 so as to provide counter bores 285. These counter bores 285 are thereby properly aligned to receive bearing sleeves 286 which are secured in position as by rivets 287. The printing frame 100 may then be removed from the fixture and mounted in position on the supporting rails 102 and 103 of the machine frame 101.

It will be observed that in the present structural section, the tongue 150 of the head forging 54 is interlocked with the side members 120 and 130 and the central plate 110 along axes or lines which constitute substantially the neutral axes of these members when the members are acting as a beam resisting forces applied in a generally vertical direction. Hence the interlocking action is attained at such a point that the structural efficiency of the metal of the plates is not materially reduced even apart from the presence of the welded connections between the several members and the tongue 150. When the welded connections have been formed between the several sheet metal members and the tongue 150, the structural strength is, of course, substantially the same as if these plates had been left unnotched or unslotted. The tongue 150 extends a substantial distance into the end of the upper arm 105 and since it is welded to the web 125W, the central plate 110 and the web 135W throughout the substantially longitudinal extent, it will be clear that the tongue 150 acts to maintain the two webs and the central plate in the desired spaced relation, thereby to impart maximum efficiency to these parts in resisting bending stresses applied to the arm 105. This action of the tongue 150 takes place whether such forces are

applied in a vertical direction tending to bend the end of the arm 105 upwardly or are applied in a horizontal direction tending to produce bending of the arm 105 either to the right or to the left.

The upper bearing supporting tube which extends through the arm 105 also functions in a similar manner to increase the effectiveness or efficiency of the metal parts of the present structural section, and it will be clear that this upper bearing supporting tube extends through the upper arm 105 relatively close to the connecting portion of the C-shaped frame. Since this upper bearing supporting tube is welded to the two webs 125W and 135W, these two webs are maintained in a predetermined spaced relation at this point. Hence, there can be no tendency for these webs to buckle or shift from the desired relationship, and the webs, therefore, function with greater efficiency in resisting the upward applied bending forces applied in the course of a printing operation or the like. This upper bearing supporting tube also functions in maintaining the desired spaced relationship of the two webs 125W and 135W in the event that forces are applied to the arm 105 tending to bend the end thereof either to the right or to the left. In addition to this functioning, this upper bearing supporting tube serves as a means for providing suitable bearing surfaces for power transmitting elements such as the rock shaft of the machine herein disclosed. In the lower arm 106 of the present structural section, the angle plate 200 functions to assure proper maintenance of the horizontal spacing of the webs 126W and 136W and of the arm 116 of the central plate with respect to these two webs. The anvil supporting plate 190 and the bracing or mounting plate 191 also act in a measure in assuring the desired spacing of the two webs 126W and 136W. Such action of the angle plate 200 and of the plates 190 and 191 takes place adjacent the end of the arm 106, while the two lower bearing supporting tubes extend through the arm 106 adjacent to the vertical connecting portion 107, and since these tubes are welded to the webs 126W and 136W, they function in maintaining the desired stiffness or rigidity of the present structural section in the same general manner as has hereinbefore been described in connection with the upper bearing tube.

The central plate 110, of course, acts to maintain the opposite flanges of the two side members 120 and 130 in the proper spaced relationship to resist bending forces applied between the ends of the arms 105 and 106.

The form of the present structural section may be termed a box section which is in the present instance of a six-sided form which not only tends to render the section pleasing in its outward appearance but also facilitates the employment of the present structural section in a printing machine such as that herein disclosed wherein the printing frame 100 is arranged at an angle to the forward edge of the table top. Through the use of this six-sided form of box section, the supporting means for the rear end of the C-shaped frame 100 may be placed directly upon one of the flanges of one of the side members of the box section, and when so mounted the formation of the supporting means is relatively simple.

Through the use of the present structural section it has been found that extremely uniform printing impressions may be made from printing devices having type lines of different lengths and

this uniformity is obtained even though there may be an extremely wide variation in the lengths of the several lines which are printed. Moreover, it has been found that with the present structural section employed as a printing frame in a printing machine, smudging of the printed impression is, in a practical sense, avoided even when a large number of carbon copies are being made. In fact, it has been found that the present structural section when so used enables the machine to produce more than double the number of clear carbon copies as compared with the number of clear carbon copies which could be produced on prior machines of the same general character. The printing frame of the present invention is comparatively light in weight so that through the use of this printing frame it has been possible to produce a printing machine which may be readily moved about an office and which does not involve problems of properly balancing the machine frame to compensate for the concentrated weight usually embodied in the stamper or platen arms in printing machines of this character heretofore used.

Since the platen structure is mounted on the printing frame herein disclosed with a power multiplying mechanism interposed between the printing frame and the platen, the forces applied to the platen operating structure from the drive mechanism carried by the main frame of the machine are comparatively slight, and all of the reactive forces resulting from the relatively large impression forming force are absorbed entirely within the printing frame and independently of the main frame. Hence it is possible to construct the machine as a whole more satisfactorily and economically than has heretofore been possible.

Thus, while I have illustrated and described a selected embodiment of my invention it is to be understood that it is capable of variation and modification and I therefore, do not wish to be limited to the precise details set forth but desire to avail myself of such changes and alterations as fall within the purview of the following claims.

I claim:

1. In a printing machine having a main supporting frame, driving means carried directly upon said main frame, means providing a platen and an anvil adapted to define a printing position, means for supporting said anvil and platen comprising a C-shaped frame formed separate from and supported directly on said main supporting frame and having end portions positioned on opposite sides of said printing position, means supporting said platen and said anvil on said end portions of said C-shaped frame and including force multiplying actuating means operable to apply impression forming force between said platen and said anvil, and means mounted in part upon said C-shaped frame and forming an operating connection between said driving means and said force multiplying actuating means.

2. In a printing machine, a main supporting frame having a supporting surface upon which a record may be supported at a printing position on said surface, driving means carried directly upon said main frame, means providing a platen and an anvil located at said printing position, means for supporting said anvil and platen comprising a rigid C-shaped frame formed separate from and supported directly on said main supporting frame and having arm portions one of which is located below said surface and the other of which is located above and in substantially spaced relation to said surface, means

supporting said platen and said anvil on the opposed end portions of the arms of said C-shaped frame, the means supporting said platen including force multiplying actuating means operable to apply impression forming force between said platen and said anvil, and means mounted in part upon said C-shaped frame and forming an operating connection between said driving means and said force multiplying actuating means.

3. In a printing machine, a main supporting frame having a supporting surface upon which a record may be supported at a printing position on said surface, driving means carried directly upon said main frame, means providing a platen and an anvil located at said printing position, means for supporting said anvil and platen comprising a rigid C-shaped frame formed separate from and supported directly on said main supporting frame and having arm portions one of which is located below said surface and the other of which is located above and in substantially spaced relation to said surface, means supporting said platen and said anvil on the opposed end portions of the arms of said C-shaped frame, the means supporting said platen including force multiplying actuating means operable to apply impression forming force between said platen and said anvil, and means mounted in part upon said C-shaped frame and forming an operating connection between said driving means and said force multiplying actuating means to apply an impression forming force between said anvil and said platen the reactive forces of which are absorbed wholly by said C-shaped frame.

4. In a structural section of the character described, a central plate of C-shaped form having an upper arm and a lower arm and a relatively wide intermediate connecting portion between corresponding ends of said arms, a pair of shell-like side members formed from sheet metal adapted to fit on opposite sides of said central plate, each of said shell-like side members being of a generally C-shaped form when viewed in elevation so as to provide an upper arm, a lower arm and an intermediate connecting portion, said arms and said intermediate connection portion of each of said shell-like side members being of generally channel-like form, providing continuous web portions with continuous flanges projecting from opposite sides of the web portions, said shell-like side members being positioned with the edges of their flanges in abutment with the opposite sides of said central plate adjacent the bordering edges thereof, said side members having the edges of their flanges welded to said central plate throughout substantially the entire extent of their mutual abutment, one arm of said central plate and the webs positioned on opposite sides of said one arm being formed with slots extending from the ends thereof substantially along the neutral axes of said one arm of said plate and said webs, and a transmitting head member having an integral interlocking tongue projecting into said slots so as to be interlocked therewith, said tongue being welded to said webs and to said arm of the central plate throughout substantially the entire extent of the bordering edges of said slots.

5. In a frame structure of the character described, a central plate of C-shaped form having an upper arm and a lower arm and a relatively wide intermediate portion, a pair of shell-like side members formed from sheet metal adapted to fit on opposite sides of said central plate, each

of said shell-like side members being of a generally C-shaped form having an upper arm, a lower arm and an intermediate connecting portion, said arms and said intermediate connecting portion of each of said shell-like side members being of generally channel-like form providing continuous web portions with continuous flanges projecting from opposite sides of the web portions, said shell-like side members being positioned with the edges of their flanges in abutment with the opposite sides of said central plate adjacent the bordering edges thereof, said side members having the edges of their flanges welded to said central plate throughout substantially the entire extent of their mutual abutment, one arm of said central plate and the webs positioned on opposite sides of said one arm being formed with slots extending from the ends thereof substantially along the neutral axes of said one arm of said plate and said webs, and a transmitting head member having an integral interlocking tongue projecting into said slots so as to be interlocked therewith, and means acting between said tongue and at least one of said webs to secure said webs and said tongue in such interlocked relation.

6. In a structural frame section of the character described, a central plate of C-shaped form having an upper arm and a lower arm and a relatively wide intermediate portion, a pair of shell-like side members formed from sheet metal and adapted to fit on opposite sides of said central plate, each of said shell-like side members being of a generally C-shaped form having an upper arm, a lower arm and an intermediate connecting portion, said arms and said intermediate connecting portion of each of said shell-like side members being of generally channel-like form providing continuous web portions with continuous flanges projecting from opposite sides of the web portions, said shell-like side members being positioned with the edges of their flanges in abutment with the opposite sides of said central plate adjacent the bordering edges thereof, said side members having the edges of their flanges welded to said central plate throughout substantially the entire extent of their mutual abutment, one arm of said central plate and the webs positioned on opposite sides of said one arm being formed with slots extending from the ends thereof substantially along the neutral axes of said one arm of said plate and said webs, a transmitting head member having an integral interlocking tongue projecting into said slots so as to be interlocked therewith, said tongue being welded to said webs and to said arm of the central plate throughout substantially the entire extent of the bordering edges of said slots, the other arm of said central plate and the flanges of the lower arms of the other arms of said shell-like members which are positioned nearest to said one arm being cut away to provide bearing surfaces on the webs of said other arms of said shell-like members and upon said other arm of said central plate, and a relatively rigid force transmitting member positioned on said bearing surfaces and welded in rigid relation thereto.

7. In a structural section of the character described, a central plate of C-shaped form having an upper arm and a lower arm and a relatively wide intermediate portion, a pair of shell-like members formed from sheet metal adapted to fit on opposite sides of said central plate, each of said shell-like side members being of a generally C-shaped form having an upper arm, a

lower arm and an intermediate connecting portion, said arms and said intermediate connecting portion of each of said shell-like side members being of generally channel-like form providing continuous web portions with continuous flanges projecting from opposite sides of the web portions, said shell-like side members being positioned with the edges of their flanges in abutment with said central plate adjacent the bordering edges thereof, said side members having the edges of their flanges welded to said central plate throughout substantially the entire extent of their mutual abutment, one arm of said central plate and the webs positioned on opposite sides of said one arm being formed with abutment surfaces adjacent the ends thereof and facing toward the said other arms, a transmitting head member having an integral attaching portion engaging said abutment surfaces, said attaching portion being welded to said abutment surfaces of said webs and of said arm of the central plate throughout substantially the entire extent of such surfaces, the said other arm of said central plate and the flanges of the lower arms of the other arms of said shell-like members which are positioned nearest to said one arm being cut away to provide bearing surfaces on the webs of said other arms of said shell-like members and upon said other arm of said central plate, and a relatively rigid force transmitting member positioned on said bearing surfaces and welded in rigid relation thereto.

8. A C-shaped frame structure of the character described comprising a continuous box section formed from sheet metal plates welded in rigid relation to each other and providing a relatively wide central portion and a pair of arms projecting integrally therefrom in generally parallel relation, said box section including a central plate welded into said box section at its opposite edges and positioned in a central plane passing through both of said arms, said central plate extending integrally through said connecting portion and throughout both of said arms, and said arms being of gradually tapering cross section so as to be somewhat smaller adjacent their ends.

9. In a frame structure for printing machines and the like, a C-shaped central plate having an intermediate web portion of substantial width and having arm portions projecting in generally parallel relation from said intermediate web portion, a pair of shell-like side members of generally C-shaped form and shaped from plate material to form channels with open side faces adapted to abut said central plate, and said C-shaped shell-like members being disposed on opposite sides of said central plate and having the edges of both of said shell-like side members welded to said central plate.

10. A frame structure of the character described adapted for use in a printing machine or the like in an angular relation to a main supporting frame, said structure comprising a C-shaped frame made from sheet metal plates welded together to form a continuous box section having a pair of generally parallel arms and a connecting intermediate portion, said box section being of six-sided form in cross section with one of such sides of said connecting portion arranged at an angle to the central plane of the C-shaped frame, which angle corresponds to the angular relationship in which the frame structure is to be mounted in a main frame, and force transmitting members interlocked with said arms adjacent the ends thereof in opposed relation-

ship to each other and welded in rigid relation upon said arms.

11. A frame structure of the character described adapted for use in a printing machine or the like in an angular relation to a main supporting frame, said structure comprising a C-shaped frame made from sheet metal plates and welded together to form a continuous box section having a pair of generally parallel arms and a connecting intermediate portion, said box section being of six-sided form in cross section with one of such sides of said connecting portion arranged at an angle to the central plane of the C-shaped frame, which angle corresponds to the angular relationship in which the frame structure is to be mounted in a main frame.

12. In a frame structure for printing machines and the like, a C-shaped central plate having an intermediate web portion of substantial width and having arm portions projecting in generally parallel relation from said intermediate web portion, a pair of shell-like side members of generally C-shaped form and shaped from plate material to form channels with open side faces adapted to register with the edges of said central plate, said C-shaped shell-like members being disposed on opposite sides of said central plate and having the edges of both of said shell-like side members welded to the registered edges of said central plate, and opposed force transmitting members secured to the ends of said arm portions.

13. A frame structure of the character described comprising a continuous box section providing a pair of generally parallel arms and an intermediate connecting section, said box section being formed from steel plate material, said arms having force transmitting members mounted on said arms in opposed relation to resist force applied therebetween which would tend to separate said arms, one of said members constituting a head forging having a generally flat head portion and an integral mounting tongue, flange means projecting from said forging between said head portion and said tongue, at least a part of said tongue being positioned within the end of the arm with said flange means closing said end of said arm, said tongue being welded to said arm, and said flange means being welded to the end edge of said arm.

14. A head forging adapted for incorporation in a platen supporting arm of box-like sectional construction, said head forging comprising a relatively flat forward portion having a mounting tongue projecting integrally therefrom and adapted to extend into and to be interlocked with and secured to such a box-like platen arm, said head forging having an upstanding flange across the upper surface defining the border between said forward portion and said tongue, a stiffening rib extending from said upstanding flange toward the end of said tongue and formed integrally with said flange and said tongue, and a stiffening rib extending from said upstanding flange for a substantial distance across the upper surface of said forward portion and said last mentioned stiffening rib being formed integrally with respect to said upstanding flange and said forward portion.

15. A head forging of the character described comprising a forward portion and an integral tongue portion and having upper and lower faces, an upstanding flange defining the border between said portions and having an integral rib projecting therefrom along said upper face of

said tongue and a second integral rib projecting along said upper face of said forward portion in the opposite direction, said forward portion having a depending skirt integrally formed about some of the edges thereof for the purpose of concealing operative mechanism normally associated with such a head forging, and a second flange depending from the lower face of said head forging and extending across a substantial portion of the lower face of said tongue, said upper and lower flanges being adapted to cooperate with the end of a hollow sheet metal arm in closing the end of such an arm and in producing an efficient force transmitting action between the head forging and such an arm.

16. A frame structure of the character described adapted for use in printing machines or the like and comprising a C-shaped frame formed from sheet metal plate material to provide a continuous box section constituting upper and lower arms generally parallel to each other and connected by an intermediate section, and force transmitting members mounted on the ends of said arms in opposed relation to resist force applied therebetween, one of said means constituting a head forging having a generally flat head portion and an integral mounting tongue both having upper and lower faces, the arm with which said head forging is associated having a pair of slots formed in its sides into which said tongue extends, said tongue being welded to said arm about the edges of said slots, said slots being located substantially midway between the upper and lower surfaces of said arm and said head forging having a flange on the upper face thereof adapted to abut those end edges of sheet metal which enter into the formation of said arm and are located above said tongue, said flange being welded to said end edges of said arm, the sheet metal of said arm beneath said tongue being cut away at an angle to provide clearance for movement of an operative part beneath said head portion and along a path disposed at an angle to the longitudinal axis of said arm, and said head forging having a downwardly extending flange formed thereon so as to be located in an angular relation across the lower face of said tongue, in which said relation said downwardly extending flange is welded to the end edges which are in abutment therewith, said downwardly extending flange serving to close the lower portion of the end of said arm.

17. A C-shaped structural section of the character described comprising a continuous box section formed from sheet metal plate material welded in rigid relation and providing a relatively wide central connecting portion and a pair of arms projecting therefrom in generally parallel relation, said arms being of gradually tapering cross section so as to be somewhat smaller adjacent their ends, force transmitting members extending across said arms adjacent the ends thereof and in opposed relation, each of said members being welded to the plate material forming opposite sides of the arm upon which such member is mounted so as to prevent relative approaching or separating movement of such sides, and a pair of metallic bearing supporting tubes one extending through each of said arms adjacent said connecting portion, said tubes being welded to the plate material of the sides of the arms so as to prevent relative separating or approaching movement of such sides adjacent said central connecting portion, and also to serve as bearing supporting means for power transmit-

ting means which may extend through said tubes.

18. A frame structure of the character described comprising a continuous box section providing a pair of generally parallel arms and an intermediate connecting section, said box section being formed from steel plates of generally channel-like form with an intermediate central plate interposed therebetween and welded to the opposite channel-like plates, said arms having force transmitting members mounted on said arms in opposed relation to resist force applied therebetween which would tend to separate said arms, said channel-like plates and said central plate having aligned apertures therein, and a bearing supporting tube extending through said aligned apertures and welded in rigid relationship to the webs of said channel-like plates so as to provide a shaft bearing means and act to hold the webs of said channel-like plates in predetermined spaced relation.

19. A frame structure of the character described comprising a continuous box section providing a pair of generally parallel arms and an intermediate connecting section, said box section being formed from steel plates of generally channel-like form with an intermediate central plate interposed therebetween and welded to the opposite channel-like plates, said arms having force transmitting members mounted on said arms in opposed relation to resist force applied therebetween which would tend to separate said arms, said channel-like plates and said central plate having aligned apertures therein located relatively close to said intermediate connecting portion, and means extending through said aligned apertures and secured in rigid relationship to the webs of said channel-like plates to prevent relative approaching or separating movement thereof when stress is applied between said arms.

20. A structural section of the character described comprising a continuous box section providing a pair of generally parallel arms and an intermediate connecting section, said box section being made up from steel plates forming side members of generally channel-like form with an intermediate central plate interposed therebetween and welded to the opposite channel-like side members, said arms having force transmitting members mounted on said arms in opposed relation to resist force applied therebetween which would tend to separate said arms, said force transmitting members being welded to said central plate and to the webs of said channel-like side members adjacent the neutral axes thereof so as to prevent relative approaching or separating movement thereof adjacent the ends of said arms, said channel-like side members and said central plate having aligned apertures therein in substantially spaced relation to the end of one of said arms, and a bearing supporting tube extending through said aligned apertures and welded in rigid relationship to the webs of said channel-like side members so as to provide a shaft bearing means and act to hold the webs of said channel-like side members in predetermined spaced relation at points spaced from the end of said one of said arms.

21. In a frame structure for printing machines and the like, a C-shaped central plate having an intermediate connecting web portion of substantial width and having arm portions projecting in generally parallel relation from said intermediate web portion, a pair of shell-like side members of generally C-shaped form and shaped from plate material to form channels with open side faces

adapted to register with the edges of said central plate, said C-shaped shell-like members being disposed on opposite sides of said central plate and having the edges of both of said shell-like side members welded to the registered edges of said central plate, and opposed force transmitting members secured to the ends of said arm portions, one of said arms having longitudi-

nally extending mounting slots formed in the shell-like members and in said central plate adjacent to and extending longitudinally along the neutral axis thereof, and one of said force transmitting members being welded in structurally interlocked relation to said mounting slots.

CARL J. HUEBER.
